UNITED STATES PATENT OFFICE

2,537,889

CORE BOX VENT

Mead L. Bricker, Detroit, Mich., assignor to Ford Motor Company, Dearborn, Mich., a corporation of Delaware

Application August 13, 1947, Serial No. 768,419

6 Claims. (Cl. 22—13)

1

This application relates to the metal founding art and more particularly to a durable and economical vent or sand retainer useful in the mass production of cores. For reasons which will become apparent below, these core box vents must be capable of rapid and economical manufacture, they must be durable under extremely destructive abrasive conditions and must effect a rapid and almost quantitative separation of sand and air.

The repetitious production of foundry cores is conventionally accomplished by molding the core material to the desired shape in a metal core box. These cores are made from a mixture which is basically moist sand to which has been added a binding agent. To fill the core boxes with this moist sand rapidly and economically and to properly compact the core, it is the usual practice to transport the sand pneumatically, using an air pressure of the order of ninety pounds per square inch. As the core box is filled with sand, some avenue of escape must be provided for the air originally present in the core box as well as the air employed to transport the sand. To be economically feasible this large volume of air must be permitted to escape rapidly and with a minimum of entrained sand.

In continuing attempts to meet these requirements, the foundry art has evolved a large variety of core box vent structures, none of which has proven completely satisfactory from both a cost and performance viewpoint. These efforts have resulted in structures ranging from a simple screen to rather complicated venting arrangements. Typical structures for this purpose are described in United States Letters Patents 2,060,350 2,126,097, 2,176,828 and 2,238,506.

The chief impediment to the success of these various structures has been the highly abrasive conditions encountered in use. The sand base of the core material is, of course, extremely abrasive and it is unavoidable that some of this abrasive sand is driven through the core box vents each time the core box is filled. This passage of abrasive sand through the core box vents at high velocity has resulted in a rapid cutting action and consequent short life of the vents. Since many core box vents are required in each core box, their maintenance is a considerable item of expense in the core room.

Accordingly it is an object of this invention to provide a core box vent which will be economical to produce, durable and highly efficient in use and quickly and easily installed in the core box.

It is a further object of this invention to pro-

2

vide an economical method for the production of core box vents using materials readily available in the foundry trade.

It is a further object of this invention to provide a core box vent which will permit the escape of a maximum volume of air in a minimum period of time and with a minimum loss of sand to the working space in the core room.

It is a further object of this invention to provide a core box vent which will not mar the smooth surface of the cores.

It is a further object of this invention to provide a resilient core box vent which will vibrate in use and so exhibit self cleaning properties.

With these and other objects in view, the invention comprises the arrangements, constructions, and combinations of the various elements of the structure described in the specification, claimed in the claims and illustrated in the accompanying drawings, in which:

Figure 1 is a plan view of the core box vent as seen from within the core box.

Figure 2 is a sectional view of applicant's core box vent taken along the line 2—2 in Figure 1.

Figure 3 is an elevation view of one stage in the manufacture of the spring element employed as the venting medium in applicant's structure.

Figure 4 is similar to Figure 1 in that it shows a plan view of a core box vent as seen from within the core box. Figure 4 differs from Figure 1 in that it depicts a variation in the type of spiral spring member.

Figure 5 is a sectional view of an alternative form of core box vent in which the cotter key is arranged to permit a certain amount of axial movement of the center of the spiral spring element.

Figure 6 is an elevation of one stage in the manufacture of the spiral spring member depicted in Figure 4.

In the interest of clarity, all of the drawings have been shown four times the actual size.

Basically, applicant's invention comprises a resilient spiral spring carried in a tubular shell member adapted to be driven into a corresponding cavity in the core box. In Figures 1 and 2 this shell is designated by the numeral 10. This shell 10 is provided with a shoulder 11 and ears 12. This shell 10 is capable of rapid production by stamping from tubing. The actual filtering of the sand from the air is effected by spiral spring 13 which is wound from a ribbon of spring steel with the long side of the ribbon parallel to the axis of the spring. This wound spiral spring 55 is inserted in the end of shell 10 remote from

shoulder 11 so that its outer convolution rests upon ears 12 and is so secured against axial movement in the direction of shoulder 11.

Recent endeavors to employ a somewhat similar structure in core box vents have encountered two difficulties. The first of these difficulties has been involved in the winding of the spring member so that the innermost convolution would be small enough to prevent the escape of substantial amounts of sand at this point. The second difficulty has been the inability to adequately support the center of the spring member against the pneumatic pressure employed in filling the cores. Any such center support is necessarily subject to the abrasive action of the sand particles and as a consequence has exhibited rather short life.

In an effort to circumvent both of these difficulties, applicant has developed the structure described in this document. Turning to Figure 3, there is depicted the spring steel ribbon 14 and cotter key 15. To produce spring 13 from ribbon 14 and cotter key 15 it is only necessary to insert the end of ribbon 14 into the eye of cotter key 15 and apply sufficient pressure to flatten the sides of the cotter key eye against the ribbon. Welding or brazing may be resorted to to insure a satisfactory joint between ribbon 14 and cotter key 15. However, this is usually not necessary as sufficient grip can be provided by simple mechanical pressure. The body of cotter key 15 can now be gripped in the collet of a spring winding machine and spring 13 readily produced.

The two halves of the body of cotter key 15 can now be bent into the position shown in Figure 2 and assembled into shell 10 as shown by that figure. When so assembled, the ends of the body of cotter key 15 rest upon shoulder 11 and serve to support the central portion of spring 13 against the pneumatic thrust. Alternatively, if such support is not necessary, the assembly of cotter key 15 and spring 13 can be placed in shell 10 with the body of the cotter key unbent, or bent to a degree less than that shown in Figure 2. If desired, any portion of the body of the cotter key 15 may be cut off prior to use to regulate the action of the vent under pressure. In any event, the head of the cotter key serves to close the center convolution of the spring 13 against sand leakage and at the same time provides a cheap and efficient arbor for winding spring 13.

Figures 4 and 6 depict another form of applicant's invention in which a different form of spiral spring 13 is employed. In this form of core box vent the two ends of the spiral spring element rest against the shell 10 and are approximately diametrically opposite each other. This type of construction gives a much stiffer spring action and is somewhat easier to fabricate. As shown in Figure 6, the spring steel ribbon 14 is secured in the eye of cotter key 15 at a point approximately intermediate its ends. When so secured the cotter key is rotated to produce the spiral spring element. Under this arrangement, the joint between the cotter key and the spring steel ribbon need not be so secure and in some circumstances can be dispensed with

entirely, the spring steel ribbon being merely thrust through the eye of the cotter key.

Figure 5 illustrates that phase of the invention in which the legs of the cotter key are shortened to allow axial movement of the center of spring 13.

From the foregoing it can be seen that applicant has provided a novel and efficient core box vent and a method of producing this core box vent from materials readily available and without the need of any special machinery.

What is claimed is:

1. A core box vent comprising an outer shell, a spiral spring element disposed in the outer shell with its plane normal to the axis of the shell and a support comprising a cotter key secured to the inner convolution of the spiral spring, the body of said cotter key being split to provide a bifurcated support for the central portion of the spring element against a portion of the shell.

2. The structure recited in claim 1 in which the ends of the split body abut the interior surface of the shell intermediate the ends of the shell.

3. The structure recited in claim 1 in which the outer convolution of the spring element is supported by the shell.

4. The structure recited in claim 1 in which the ends of the cotter key remote from the cotter key eye terminate short of a shoulder provided on the outer shell so that a limited axial movement of the inner convolution of the spiral spring element is provided.

5. A core box vent comprising a cotter key and a spiral resilient element, the body of said cotter key being split so that the two ends thereof are separated a substantial distance and the inner convolution of said spiral resilient element being secured in the eye of the cotter key.

6. A core box vent comprising a cotter key and a spiral resilient element, the body of said cotter key being split so that the two ends thereof are separated a substantial distance and the inner convolution of said spiral resilient element being secured in the eye of the cotter key at a locale intermediate the ends of the spiral element.
